OVEN DOOR, FRAME, AND FASTENING DEVICE

Application filed December 15, 1926. Serial No. 154,875.

The present invention relates to by-product coke ovens and more particularly to that part of such coke ovens which is concerned with the means for closing the ends of the coking 5 chambers.

In the construction and operation of by-product coke ovens, particularly of the horizontal flue type, it is well known that the matter of a satisfactory oven closure has presented a difficult problem. A proper solution of this problem required the elimination of leakage of coke oven gas from the coking chamber and of flue gas from the heating flues, the prevention of the destruction of the 10 door frame itself due to breakage, and the provision of as great a coking space as possible in the coking ovens.

Heretofore, various structures have been proposed in the effort to partially solve the 20 aforesaid problem but all of these proposals have been unsatisfactory because of one reason or another. It is an object of the present invention to provide an improved oven closure including a novel door frame and 25 novel fastening means therefor which will reliably prevent gas leakage adjacent the said structure either from the heating flue system or the coking chamber, which will reduce or substantially eliminate the break- 30 age of the door frames themselves, and which will provide a maximum coking space in the coking chambers. A further object is to pro- 35 vide such a structure which is simple in construction, has a low initial cost, and a relatively negligible upkeep.

Other features and advantages of the invention will be made clear by a description of a preferred embodiment thereof as illustrated in the accompanying drawings, in 40 which:—

Fig. 1 is an elevation of a portion of a by-product coke oven illustrating an oven frame and door structure constructed according to our invention:

45 Figs. 2 and 3 are sectional views on the lines 2—2 and 3—3 respectively of Fig. 1;

Figure 4 is an enlarged sectional view on the line 4—4 of Fig. 1,

50 Fig. 5 illustrates a detail view on an enlarged scale of a fastening bracket and

thrust bar shown in Fig. 1 for holding our improved oven frame in position;

Fig. 6 is a sectional view on the line 6—6 of Fig. 5; and

Fig. 7 is a perspective view of a wedge 55 used to maintain the frame in position.

In the drawings the numeral 1 (see Fig. 3) designates a part of a coking oven of a battery of such ovens positioned between adjacent division walls 6 of massive construction. Each oven 1 has a horizontal heating flue system 2 of well known type at each side thereof adjacent to the division walls 6 but of lesser longitudinal extent and they define between their respective side walls 4 the extent of available coking space in the chambers 1. The outer and inner walls 3 and 4 of this flue system fit against and preferably make a strong joint with end members or bricks 5 which are faced with jamb bricks 7. At appropriate positions a plurality of burners 8 (see Fig. 1) protrude through these bricks 7 and 5 into the heating flues at each end of the oven. Air to support the combustion of the fuel gas issuing from these burners flows from well known regenerators or the like (not shown) located underneath the coking ovens. The heat from the burning gas distills or evolves the volatile products, so-called coke oven gases, from the coal or the charge in the coking chambers 1. The coke oven gases, as is well known, leave the oven through the usual off-take ports (not shown) located in the upper part of 60 each oven. The products of combustion from 65 the heating flues flow to a chimney or stack via appropriate outlets and regenerators 70 (not shown).

Our improved oven frame designated generally by 11 (see Fig. 1) frames the entire 75 periphery of the outer face of the end walls of the coking chambers 1 but leaves the entrance to or the exit from said chambers unobstructed. This frame is seated on brick-work 17 below the oven floor 18 (see Fig. 2) 80 and is preferably made as an integral metal casting having a substantially trapezoidal cross-section (see Fig. 3) with inner sloping 85 sides, with a retaining rib or inner flange 16 projecting from the corner of said section 90 95 100

and engaging jamb bricks 7, and with an outer flange, said inner and outer flanges and inward continuations of said inner flanges constituting a door abutment. Within the frame 11, webs 13 are positioned at spaced points to reinforce the casting. By seating the rib 16 in a corresponding recess in the jamb bricks 7, the flue system is lined up properly and leakage of gas from the coking chamber between the jamb bricks and the rear of the frame is minimized.

A plurality of spaced brackets 19 are secured at appropriate distances from each other to buck-stays 20 in any suitable manner, such as by bolts 10. Each bracket has a recess 40 (Fig. 5) in which a reversible thrust bar 21 (Fig. 6) is seated. This thrust bar projects in front of the frame 11 and is provided with a seat 50 which when the thrust bar is correctly supported in the brackets 19 is located sufficiently close to the outer face of the framework 12 to allow a wedge 15 (Figs. 3 and 7) to be driven in between and to be frictionally maintained in position while preserving the wedging strain. The wedges are furthermore operative upon the thrust bars and the oven frame in such manner as to exercise a retaining force which is substantially coincident with the center line of the frame 11, thereby eliminating eccentric stresses which would tend to cause breakage of the oven frame. At the same time the construction minimizes the liability of opening of the jamb bricks of the oven chambers, and, thus, serves to prevent leakage therefrom.

The thrust bars 21 (Fig. 3) are shown as having a slight bend therein the purpose of which is to allow for an adjustment of position as between their seats 50 and the outer face of the framework 12. Thus if due to expansion of the flue system, the seat 50 of the thrust bar 21 is found to be too close to the face of framework 12, the thrust bars can be re-seated in their retaining recesses in a reversed position with the arms 21 pointing away from the coking chamber instead of pointing toward the chamber as shown in Fig. 3, and in that position there will then be sufficient room for the wedge. In case it is desired to provide a thrust bar with more than two positions for adjustment, the straight sides of the bars can be modified to provide another adjustable position. Furthermore, by bending a thrust bar in a plane perpendicular to that illustrated in Fig. 6, four different positions for adjustment will be available.

Between the inner side walls of the frame 11 and the jamb bricks 7 a steel plate 22 (Fig. 3), smooth on its outside face and preferably also on its inner face, may be interposed for the purpose of maintaining as snug a fit as possible between the frame 11 and bricks 7, when under pressure of wedges 15. In this

way gas leakage between the frame and the bricks 7 is further prevented. The steel contacting plate 22 not only reinforces the cast frame 11 but also offers a sliding surface for the jamb bricks during expansion and contraction. At the top of the oven, steel plates like 22 are not required but the casting 11 at this point may be thickened (see Fig. 2) so that the rear of the frame inclusive of plates 22 presents a flat seating surface throughout without requiring special construction of the brickwork to seal the frame against the brick facing.

A door 23 is seated in the cast frame 11 and is preferably made with a metallic element 80 having edge surfaces substantially perpendicular to the plane of the door, such as a casting of cast iron, provided with a steel contacting plate 24 at each side thereof, said plates 24 being riveted or otherwise fastened 85 to the edge surfaces of the said casing and projecting from the element, so that the edge of each plate projects rearwardly from the door toward the door frame. When the door is in position, each edge contacts with the adjacent face of the frame. The inner wall of the door is lined with refractory bricks 25 in any approved manner. In order to retain the door in a closed position locking bars 26 (Figs. 1 and 2) and latches 27 of well known type are used, projecting rail members 29 serving as a guide for the bars 26 being carried by the door casting. An opening 28 in the door casting (Figs. 1 and 2) is provided for a door extractor so that the door 100 may be removed in a mechanical manner. It will be observed that when the door is set in place against the frame, the line of contact will be the one defined by the inner flat faces of the steel plates 24, which are part of the door structure, against a flat part of the door frame at the point where the latter is reinforced by rib 16 (see Fig. 3). In this respect the present construction differs from the standard practice of endeavoring to make 105 a line contact between a sloping side face of the door and an angular part of the frame or vice versa. The advantage of the new structure is to provide a flat surface contact throughout, the surfaces being in contact at 110 substantially right angles to the direction of the forces which hold the door against the frame, and thus to provide a continuously 115 tight seat irrespective of irregularities in the contour of the door or of the frame such as 120 might result from uneven heat distribution at the two sides of the coking chamber.

It will be observed that our invention provides a coke oven structure with an oven door frame and fastening therefor which substantially prevents leakage of gas from the heating flues or the oven chambers, which substantially eliminates destruction of door frames due to eccentric stresses and to inequalities of temperature conditions and re- 125 130

sulting uneven expansion of the oven structure, which provides a support to keep the flues in position and to decrease gas leakage between the oven door frame and the oven jambs, which utilizes a thrust bar of cantilever type and an associated wedge to accommodate the expansion of the oven flue system and to transfer the thrust due to expansion from the door frame to the buck-
5 stays, and which includes an integral cast structural frame with flat faces to effect a substantially gas-tight arrangement.

It will be further noted that our invention provides a construction adapted to facilitate 15 the assembly or the dismantling of the oven frame of any coking chamber without affecting adjacent chambers because the brackets associated with any one chamber can be separately removed and each frame can be lifted 20 as a separate unit from its seat.

Furthermore, our improved oven frame and door provides an oven chamber with approximately maximum coking space for a given structure. Since the oven frame is supported 25 from the buck-stays (which project outwardly from the division walls) it can be positioned close to the outer end of the division walls with an ample allowance for the jamb bricks and the door linings so that 30 the inner faces of the two doors enclosing the two ends of the oven chamber are located at substantially a maximum distance apart, thus providing substantially the maximum coking space permissible by the oven structure.
35

We claim:

1. In a coke oven battery comprising open ended coking chambers alternating side by side with division walls having heating flue 40 systems adjacent to the sides thereof and buck-stays adjacent to the ends of said division walls, a closure structure for a coking chamber comprising a metal frame surrounding an end opening of the coking chamber, and means supported from the buck-stays for holding the frame in place by a pressure contact at a plurality of points between said means and said frame.
45

2. In a coke oven battery comprising horizontal coking chambers alternating side by side with division walls having heating flue systems adjacent to the sides thereof and buck-stays adjacent to the ends of said division walls, a closure structure for a coking chamber comprising a metal frame surrounding an end opening of the coking chamber, and means supported from the buck-
50 stays for holding the frame in place by a pressure contact at a plurality of points between said means and said frame, the pressure contact points being located in approximately the longitudinal central region of the side walls of said frame as well as of the end walls of the flue systems.
55

3. In a coke oven battery comprising hori-

zontal coking chambers alternating side by side with division walls having heating flue systems adjacent to the sides thereof and buck-stays adjacent to the ends of said division walls, a closure structure for a coking chamber comprising a metal frame surrounding an end opening of the coking chamber, means supported from the buck-stays for holding the frame in place by a wedge-controlled pressure contact at a plurality of 75 points between said means and said frame, the pressure contact points being located in approximately the longitudinal central region of the side walls of said frame.
80

4. A structure such as set forth in claim 1, in which the lateral ends of the flue systems are provided with jamb bricks and in which a steel plate having sliding engagement with the faces of the jamb bricks is interposed between the inner surfaces of the 35 side walls of the door frame and said jamb bricks.
85

5. A structure such as set forth in claim 1, in which one edge of the frame is developed as a rib while the lateral end bricks for the flue systems are provided with seats for such ribs, said seats and ribs being located near that edge of the frame which is nearest the center line of the coking chamber.
90

6. A structure such as set forth in claim 1, in which the lateral ends of the flue systems are provided with jamb bricks and in which a steel plate having sliding engagement with the faces of the jamb bricks is interposed between the inner surfaces of the 100 side walls of the door frame and said jamb bricks, each inner lateral edge of the door frame being developed as a rib while the jamb bricks are provided with seats for such ribs, said seats and ribs being located near 105 that edge of the frame which is nearest the center line of the coking chamber.
110

7. In a coke oven battery comprising horizontal coking chambers alternating side by side with division walls having heating flue systems adjacent to the sides thereof and buck-stays adjacent to the ends of said division walls, an opening in each end of each coking chamber, end bricks for the flue systems, a metal door frame surrounding each of the end openings and seated snugly against the end bricks of the flue systems, means supported from the buck-stays for holding the frame in place by a pressure contact at a plurality of points between said means and said frame, the pressure contact points being located in approximately the longitudinal central region of the side walls of said frame, a door seated snugly against 115 said frame.
120

8. In a coke oven battery comprising horizontal coking chambers alternating side by side with division walls having heating flue systems adjacent to the sides thereof and buck-stays adjacent to the ends of said divi-
125

sion walls, a closure structure for a coking chamber comprising lateral end bricks for the flue systems, a metal frame surrounding an end opening of the coking chamber and seated snugly against the end bricks of the flue systems, means supported from the buck-stays for holding the frame in place by a pressure contact at a plurality of points between said means and said frame, the pressure contact points being located in approximately the longitudinal central region of the side walls of said frame, and a door fitting in said frame to close the end of the coking chamber constituted of a metallic casing and refractory material carried by said casing, said door having a metallic bar secured to each side thereof in such a manner that the bar contacts snugly against the face of the frame, forms a recess between the door and itself, and provides a clearance between the door and a retaining strip on the frame as well as between itself and the frame near the seat.

9. A frame and door for a coking chamber of a by-product coke oven battery, which comprises an integral cast metallic frame having longitudinal seating faces on the sides thereof, a cast metallic door casing fitting within but spaced from said metallic frame, having its inner face lined with refractory material and having steel plates secured to the sides, said steel plates having flat longitudinal edge faces, one of the flat longitudinal edge faces of said plates extending beyond the door casing and being adapted to make edge contact with the longitudinal seating faces on the sides of said frame so as to provide a substantially gas-tight joint.

10. A frame and door for a by-product coke oven having heating flue systems adjacent each coking chamber, which comprises jamb bricks at the lateral ends of the heating flue systems, a cast metallic frame for said oven, the longitudinal sides of which have a substantially trapezoidal shaped cross-section with reinforcing webs located at spaced points and with a retaining rib extending along the inner edge of said frame, said rib engaging the jamb bricks thereby keeping the flue system lined up, and a metallic door element fitting said frame and lined with refractory material and having a metallic part thereof engage the outer face of said retaining rib so as to provide a substantially gas-tight joint.

11. In a coke oven battery comprising horizontal coking chambers alternating side by side with division walls having heating flue systems adjacent to the sides thereof and buck-stays adjacent to the ends of said division walls, the combination of jamb bricks at the lateral ends of the flue systems, a metallic door frame having a flat face seated against the jamb bricks, a plurality of spaced thrust bars rigidly supported from said

buck-stays and wedges engaging the outer surface of said frame and the inner faces of the thrust bars to hold the frame in position, an oven door fitting said frame and means for making a flat metallic joint between the door and its frame.

12. In a coke oven battery comprising horizontal coking chambers alternating side by side with division walls having heating flue systems adjacent to the sides thereof and buck-stays adjacent to the ends of said division walls, the combination of jamb bricks at the lateral ends of the heating flue systems, a cast integral metallic door frame for each of said ovens, the said frame having a flat-surfaced seating portion for a door and a flat inner face and a retaining rib at the inner edge thereof adapted to engage said jamb bricks, a flat steel plate interposed between said flat inner face of the frame and the said jamb bricks, a plurality of cantilever thrust bars, brackets secured to said buck-stays at spaced points for rigidly supporting the thrust bars, wedges to cause strain as between the thrust bars and the frame, the said thrust bars being shaped to engage said wedges and thereby hold said door frame tightly in position against said steel plates and said jamb bricks, and an oven door having a flat metallic surface engaging the corresponding flat surface on said door frame.

13. A coke oven door assembly comprising in combination a metallic frame having sides, inclined with respect to a vertical plane at right angles to the coke oven flanges extending from said sides in both horizontal directions toward the coke oven chamber and away from the chamber, and inner continuations of the inner flanges extending toward the chamber constituting a door abutment, a door including a metallic casing with edge surfaces substantially perpendicular to the plane of the door and metal strips riveted to the edge surfaces and projecting from the casing, said strips having edge contact with the abutment, latches extending from the outer flanges, and locking bars engaging said latches and said door.

In testimony whereof we have hereunto set our hands.

HERBERT EDWARD DUNKLE.
JULIUS BECKER.

CERTIFICATE OF CORRECTION.

Patent No. 1,878,680.

September 20, 1932.

HERBERT EDWARD DUNKLE ET AL.

It is hereby certified that error appears in the printed specification of the above numbered patent requiring correction as follows: Page 4, line 100, claim 13, after the word "oven" insert a comma; and lines 103 and 104, same claim, strike out the word "inner"; and that the said Letters Patent should be read with these corrections therein that the same may conform to the record of the case in the Patent Office.

Signed and sealed this 29th day of November, A. D. 1932.
